CLAIM

I claim the ornamental design for a spray cap, as shown.

DESCRIPTION

FIG. 1 is a perspective view of spray cap showing my new design;

FIG. 2 is a front view of the spray cap;

FIG. 3 is a right side view of the spray cap;

FIG. 4 is a back view of the spray cap;

FIG. 5 is a top view of the spray cap; and,

FIG. 6 is a left side view of the spray cap.
